UNITED STATES PATENT OFFICE.

JAMES LAMONT, OF SAG HARBOR, NEW YORK, ASSIGNOR TO FAHYS
WATCH CASE COMPANY, OF SAME PLACE.

WATCH-CASE.

SPECIFICATION forming part of Letters Patent No. 321,826, dated July 7, 1885.

Application filed February 25, 1885. (No model.)

To all whom it may concern:

Be it known that I, JAMES LAMONT, a citizen of the United States, residing at Sag Harbor, Suffolk county, New York, have invented 5 new and useful Improvements in Watch-Cases, of which the following is a specification.

My invention relates to watch-cases, and its objects are to furnish means whereby the lifting and hook springs may be retained in position in the case-center without the use of screws, to furnish a ring for the movement, which forms an effectual dust-protector therefor, and which, secured within the case-center, retains the movement therein, and also stiffens 10 and supports the back flat of the case-center, and also to furnish ready and convenient means for the securement of the ring and movement within the case-center without any of the means of attachment being visible in the ordinary use of a watch.

To these ends, I take a watch-case entire, made hollow on its interior, as usual, and provided with the recesses in its front bezel, or snap, through which the free ends of the 15 springs pass to operate on the front cap. In the hollow are secured, by soldering or otherwise, two pillars or posts reaching from front to back of the hollow of the center, and having their exterior edge flush with the inner rim of 20 the front back-snap. These pillars or posts are located at such points that the inner ends of the springs shall rest thereagainst when in position, and be prevented thereby from further backward movement, movement in the 25 opposite direction being prevented by the active ends of the springs taking in the recesses in the front back center snap and in the ring, one post or pillar being arranged for each spring. In order to prevent the springs from 30 slipping out of the hollow toward the interior, lugs are formed, one for each spring, upon the back of the hollow, extending, say, half-way, or thereabout, toward the front, behind which the springs are to be slipped into position. 35 The ring used has an internally-projecting flange at its bottom, upon which the back plate of the movement will rest, while on the extension of the inner edge of the flange, a small shoulder is formed, just fitting within 40 the back of the center, the movement being 45

secured to this back flange in the usual manner. At its top the ring is formed, with an internal shoulder for supporting the front plate of the movement, while on the outside thereof is formed a front snap for securing 55 thereto the bezel. This ring is furnished with recesses at proper points in its periphery, through which pass the outwardly-projecting and active ends of the springs. These recesses are only upon the outer body of the ring, and 60 do not extend through the bezel-snap. To secure the ring within the case-center at proper points to coincide with the pillars or posts, two small recesses are formed on the shoulder 65 of the ring outside of the bezel-snap, and similar recesses are formed, one in each post, these recesses being each the half of a screw-hole, regularly tapped or threaded, so that when in position the recesses registering two complete screw-holes are formed, in which may be seated 70 the screws for retaining the ring in the case-center, while the heads thereof are concealed by the bezel.

The construction thus generally described may be better understood by reference to the 75 drawings, in which Figure 1 is a perspective of case-center and ring embodying my invention; Fig. 2, a plan view of the ring; Fig. 3, a section on line xx , Fig. 1; Fig. 4, a section on line xx , Fig. 3; Fig. 5, a section of the ring. 80 Fig. 6 is a section of the ring and center on line zz of Fig. 2; and Fig. 7 a section taken on the line ab of Fig. 4.

In these drawings, the reference-numeral 1 indicates the case-center, having the usual interior hollow, 23. Upon its front it is formed with a front back-snap, 2, and upon its back with the cup-snap 4 and back-snap 3, and the usual pendant, 20, is attached to it.

5 is the lifting-spring, and 6 the lock-spring, 90 the latter arranged to be operated on by the push.

7 7 are posts or stops within and extending entirely across the hollow frame front to back of the case-center. One is arranged for each 95 spring and at such points from the recesses in which the outer ends of the springs take that the inner ends of the springs may take against and be stopped thereby, as shown in Fig. 4. The inner sides of these posts are just flush 100

with the inner edge of the front flat of the case-center. At points about midway between these posts and the recesses through which the free ends of the springs pass, lugs 5 or projections 8 are fixed to or formed on the inner base of the case-center, extending upwardly, say, half the width of the springs. In the inner side and at the top of each post or pillar a recess, 9, is formed, each recess being one-half of a screw-hole, and is finished as such.

10 is the ring, of a size to fit snugly within the case-center and having the recesses 21 in its outer periphery to register with the corresponding recesses in the inner rim of the top of the case center, and forming passages for the action ends of the springs. At its top edge it has the bezel-snap 11, for receiving the bezel, and an interior shoulder, 12, on 15 which rests the front plate of an introduced movement. At its base upon the interior is a flange for raising the back plate of such movement, and there is also a flat, 14, adapted to take upon the interior of the back flat of the center, and which is bounded by a small projecting rim, 15, forming a flat which fits within the interior rim of the back of the case-center, whereby a dust-proof joint at that point of the center and ring is formed. The flat 14 20 is made quite broad and passes under the back flat of the center case, supporting it, thereby adding to its strength and preventing its being bent or jammed out of shape by the action of the cap thereon. In the exterior of 25 the periphery of the ring and at its top two recesses, 22, are formed, of the same character as recesses 9 9, and at such points that when the ring is placed in proper position in the case-center, the recesses 9 and 22 will register and form a complete screw-hole, the introduction of a screw therein serving to securely fasten the ring within the case.

In using this construction of case the springs are to be slipped back of the lugs 8 until their 45 inner ends abut against the stops or posts 7, when the free ends of the springs will take in their appropriate recesses, the latter preventing movement in one direction, the posts or stops preventing movement in the other, while 50 the lugs prevent slipping out of the hollow toward the interior. Thus they are held in place without any tapping of the case-center or the spring, and disfigurement of the case-center and weakening of the springs avoided. 55 In addition, secure retention of the springs in position is insured by the ring, which fits within the case-center so snugly that its outer periphery bears against the thicker and inner end of the springs, the posts and lugs, however, serving to retain the springs in position whenever and while the ring is removed from the center. The hollow can be readily got at for the removal of dust, rouge, &c., which may have found its way therein and for its 65 thorough cleansing and drying.

The springs in position, the ring is put into

place and secured by screws passing into the screw-holes formed by the recesses 9 22, as before explained. The bezel being then snapped thereon, the heads of these screws are entirely concealed. The construction of this ring causes it also to form an efficient dust-ring for the movement, protecting it entirely against any dust or foreign matters which might sift through the pendant or the joints into the 75 hollow.

It is evident that the mode herein shown of securing the ring and its contained movement within the case-center is applicable to open-faced as well as hunting-case watches, in 80 which former case the springs 5 6 would of course be dispensed with, as might be the lugs 8.

In forming the recesses 9 22, I have found it preferable to first place the ring in position with the recesses therein and in the posts unformed, and then tap the screw-holes in both, the tap acting in both equally and forming a half in each.

When, however, it is desired to dispense 90 with the pillars or posts, the improved ring may still be used, it being secured within the case-center by screws passing through holes 25 in the back flat of the center into holes 24 in the flat 14 of the ring, as shown in Fig. 6. 95

Having thus described my invention, what I claim is—

1. A case-center having recesses for receiving the free ends of the lifting and holding springs, posts or stops secured therein for preventing backward movement of the springs, and lugs for confining them in position, substantially as described. 100

2. A case-center having posts or stops across the interior of its hollow and lugs upon one 105 base thereof, whereby the lifting and holding springs are secured in position, substantially as described.

3. In a watch-center, the combination of 110 springs 5 6, posts or stops 7, and lugs 8, substantially as described.

4. In a watch-case, the combination of a case-center, posts, or stops extending across its hollow for the ends of the springs to abut against, and provided with screw-threaded 115 semicircular recesses, and a ring having similar recesses, whereby, when the parts are arranged for the recesses to register, screw-holes for securing the ring to the center by means of the posts or stops are formed, substantially 120 as described.

5. The combination, with a case-center, of a ring having flat 14 and shoulder 15, adapted to form a double joint with the back of the center and support the cap-flat of the center, 125 substantially as described.

6. The combination of a watch-case center having posts 7, with recesses 9, and a ring having similar recesses 22, substantially as described. 130

7. A watch-case center having posts 7 with interior recesses, 9, formed and finished as the

halves of screw-holes, substantially as described.

8. The combination of the case-center, the posts 7, having recesses 9, the lugs 8, a spring 5 or springs, 5 6, and the ring 10, having recesses 22, the recesses being finished and formed each as the half of a screw-hole, substantially as described.

In testimony whereof I affix my signature in presence of two witnesses.

JAMES LAMONT.
